UNITED STATES PATENT OFFICE

GUSTAVE O. DEGENER, OF BROOKLYN, NEW YORK, ASSIGNOR TO ROYAL TYPEWRITER COMPANY, INC., OF NEW YORK, N. Y., A CORPORATION OF NEW YORK

MANIFOLDING DEVICE

Application filed September 3, 1926. Serial No. 133,437.

This invention relates to an improved construction which may be attached to the carriage of any standard typewriting machine without much modification in the machine itself, and is designed for the purpose of writing on continuous billing forms which are frequently fed to the machine in lengths of several hundred feet.

The invention primarily has for its object 10 to provide a new and improved manifolding device in the character of an interfold billing machine adapted for writing upon superposed continuous work sheets or webs of connected forms and wherein is provided means 15 to feed or line space the webs past a platen and over a frame on which said webs are so positioned as to provide for complete visibility, thereby greatly facilitating the writing operation and reducing to the minimum the 20 possibility of error, and for feeding narrow carbon strips interleaved with the webs across the printing line and which after being so fed may be torn off and thrown away, the use of carbon strips insuring uniformly inked carbons at all times and eliminating the great 25 waste of time and material and other disadvantages incident to the use of carbon sheets.

Another object of the invention is to provide means separate from the platen to effect line space movements to the superposed work sheets, said means including a clamp which securely grips the leading ends of the work sheets to thereby maintain the superposed forms of the work sheets in registration 35 during the entire time said work sheets are fed through the machine.

Another object of my invention is to provide means for positioning the webs and carbon strips in tight contact relation against 40 the curved printing line of the platen preparatory to certain printing operations whereby clear impressions will be made on the various webs, and to relieve the tight contact relation between the webs and carbon 45 strips, and the platen, prior to feeding or line spacing movements of the webs whereby said webs will be disposed in a substantially flat condition while being fed freely relative to the platen and without dragging the transversely extending carbon strips therewith.

The invention herein claimed includes means for feeding these forms or work sheets upwardly past a guide, thence past the platen, and thence upwardly over a frame which extends upwardly from the delivery side of 55 the platen.

Another object of the invention is to construct and mount the frame over which the webs are fed so that said frame may be swung between rearwardly inclined and substantially vertical positions, and to provide means to so hold and guide the webs that when the frame is in the inclined position the written portions of the webs will be presented to full view of the operator and in substantially 60 right angular relation to her line of vision, and whereby the web sheets and carbon strips will be compacted tightly against the printing line of the platen and form a close pack so that the impact of the type bars will carry 65 through to the last copy with a light staccato blow and thus insure uniformly sharp, clear carbon copies, and when the frame is moved to the vertical position, the webs will be disposed substantially flat and the prior compacted condition of the web sheets will be relieved to facilitate line spacing of the webs without dragging the interleaved carbon strips or smutting the web sheets by dragging over the carbon strips while in tight relation. 70

Another object of the invention is to provide means whereby the swinging or moving of the frame is effected by mechanism controlled by the same lever that effects line spacing of the webs, and feed of the carbon strips, and to so time the operation of these devices that the line spacing operation and strip feed operation are effected while the frame is in the vertical position only. 75

Another object of the invention is to provide novel means to feed the carbon strips, including means to adjust the degree of feed. 80

Another object of the invention is to provide means to impose a tension on the carbon strips which is active at intervals only to prevent carbon strip movement with the webs in a direction transverse to the direction of carbon strip feed. 85

Another object of the invention is to provide means to impose a constant tension on 100

the carbon strips, and an auxiliary or added tension which is active at intervals only to prevent carbon strip movement with the webs in a direction transverse to the direction of 5 carbon strip feed.

Another object of the invention is to supply the carbon strips from individual spools mounted on a spindle projecting from and supported by the machine frame so that the 10 movable carriage is relieved of the weight of said spools.

Another object of the invention is to provide a novel line spacing means which includes a truck movably mounted on the 15 swingable frame and having a clamp thereon to receive and hold the leading ends of the work sheets, and means to move the truck upwardly step-by-step to effect line spacing of the work sheets.

20 The invention also comprehends means whereby the truck may be released after each form has been completely written from clamping engagement with the work sheets and from the line space movement effecting 25 means, so that said truck may be lowered or returned to its starting position after which the clamp is caused to grip the next form preparatory to line spacing thereof, the clamp being utilized as a straight edge when tearing 30 off the completed form.

Another object of the invention is to mount the platen directly on the frame and to provide novel means for swinging the frame to impart thereto a floating pivotal movement 35 whereby the upper and lower ends of the frame will be caused to move reversely, that is, one end moves forwardly as the other end moves rearwardly and vice versa, to thereby cause the platen to engage and tightly 40 compact the work sheets in curved condition at the printing line of the platen during printing intervals, and to move the platen to relieve the compacting contact and also to dispose the work sheets substantially flat and 45 vertical during line spacing intervals.

The invention is illustrated as applied to the well known standard Royal machine which employs the usual inking ribbon, but as will be obvious it is capable of application 50 to other types of machines. It is also not limited to a typewriting machine but may be applied to a combined typewriting and computing machine or other machines of this general character. Certain features of the 55 invention are not limited to a machine in which work sheets travel in letter space direction relatively to the type, but may be embodied in a machine in which the type travels relatively to the work sheet for letter 60 spacing or in which there may be no letter spacing movement at all.

Further detail features of the invention will be apparent from the following description and the appended claims.

65 In the drawings:

Figure 1 is a side elevation of the device applied to a typewriting machine and embodying one form of work sheet feeding means, and carbon strip support, the operating mechanism for swinging the frame and 70 for actuating the line spacing mechanism, also the carbon strip feeding devices being omitted.

Figure 2 is a section on the line 2—2 of 75 Figure 1.

Figure 3 is a rear view of the construction disclosed in Figure 1, the specific step-by-step mechanism for line spacing the truck being omitted.

Figure 4 is a top plan view of a portion of 80 the guiding means for the carbon strips of this modification.

Figure 5 is a front elevation of the device attached to the carriage of a typewriting machine.

Figure 6 is a fore and aft section through the device as shown in Figure 5 but illustrating a modified form of carbon strip support and work sheet feeding means.

Figure 7 is a section on the line 7—7 of 90 Figure 6.

Figure 8 is a fragmentary view showing the relation of the work sheets to the platen when the frame is in vertical position.

Figure 9 is a top plan view, parts being 95 broken away and in section, of the means for supporting the carbon strips shown in Figure 8, and feeding means for these strips which is common to both modifications, the constant light tension lever being moved to 100 the release position.

Figure 10 is a top plan view, partly in section, of a modified form of the construction at the left hand side of Figure 9 for imposing additional frictional resistance upon the 105 carbon strips.

Figure 11 is a plan view of a portion of the mechanism at the left hand side of the machine, showing part of the operating means for line spacing the work sheets, for feeding the ribbon, and for swinging the frame.

Figure 12 is a side view of a retent bar forming a part of the line spacing mechanism for the work sheets.

Figure 13 is a top plan view with parts in section of the means for imparting lengthwise feed movement to the carbon strips.

Figure 14 is a view taken at right angles to Figure 13, parts being shown in section.

Figure 15 is a detail plan view illustrating a means for placing frictional resistance upon the ribbons or carbon strips.

Figure 16 is a longitudinal section through the construction shown in Figure 15.

Figure 17 is a section on the line 17—17 of Figure 13.

Figure 18 is a disassembled view of various parts of the hand controlled mechanism for operating the various instrumentalities.

Figure 19 is a view from the left hand side of Figure 7 on an enlarged scale, showing the means for releasing the truck and the detent feeding mechanism.

5 Figures 20, 21 and 22 are fragmentary plan views illustrating the parts shown in Figure 11, and diagrammatically illustrate the respective positions of the control lever in the course of moving the frame to the vertical position and for applying the additional tension to the carbon strips, the position at which the frame is fully swung to the vertical position and the additional resistance fully applied to the carbon strips, and
10 15 the position at which the additional resistance has been released and the line spacing mechanism and the carbon strip feed about to be actuated, the frame being held in the vertical position at this time.
20 As previously stated, the invention may be embodied in various types of typewriting and analogous machines and there has accordingly been illustrated only enough of the usual typewriting machine to show the position of the mechanism comprising this invention with relation thereto. The drawings illustrate a main frame A, a carriage having side plates B, the carriage having a rail C which is adapted to travel upon a main rail
25 30 35 D by means of interposed ball bearings. A type bar E is illustrated in the position which it occupies just prior to printing. The tabular stop rod F is carried by the side plates B of the carriage and is of the usual construction. The paper table G is or may be of the usual construction and the work sheets H are fed thereover to the platen.

The usual platen is removed, but the platen shaft or axle 1 is retained and is journaled in the side plates of the carriage. Below this the shaft 2 is also attached by screws 3 to the side plates, and a chute 4 is fastened to blocks 5 which are carried on the shaft 2. At each side of the machine and just inside the blocks 4 is an arm 6. At the right hand side of the machine the arm 6 is pivoted at 7 to an inverted U-shaped or channel-shaped member 8 and at the left hand side of the machine, the arm 6 is similarly pivoted to a similar channel member 9. These two members are connected at their top by screws 11 to a rod 10. The arms 6, side members 8 and 9, and rod 10, therefore, constitute a frame and since the members 8 and 9 are pivoted to the arms 6, it is obvious that the frame may be swung about this pivot point. The outside flange of each channel member 8 and 9 has an extension 12 clearly shown in Figure 6 provided with an arc-shaped slot 13 which engages the platen axle 1. A platen 14 which is preferably formed of brass or similar metal, is attached by screws 15 to the channel members 8 and 9. As shown in Figure 6, the work sheets H are fed over the paper table G to the chute 4 and thence upwardly over the platen 14 and lie

upon the frame at the delivery side of the machine.

The same screws 11 which attach the rod 10 to the side bars of the frame also fasten to said frame the upper ends of links 16 which are pivoted at their lower ends at 17 to links 18 mounted on a rockshaft 19 extending from one side to the other of the work sheet supporting frame. Each link 16 has an offset lug 20 adapted to engage the link 18 when the parts are in the operated or full line position of Figure 6. The shaft 19 has a downwardly extending arm 21, the purpose of which will be hereinafter set forth.

From the foregoing it will be observed that the frame X is pivoted at its lower end to swing rearwardly to a rearwardly inclined position and forwardly to a substantially vertical position, and that the platen 14 is fixed to the lower end of the frame to move therewith whereby the platen will be bodily moved rearwardly when the frame is swung forwardly and moved forwardly to its original position when the frame is swung rearwardly.

Supported on the frame X for movements toward and from the platen is a truck or holder Y having means for clamping the leading ends of the work sheets thereto. This truck or holder Y is normally located at the lower end of the frame X and means is provided for moving the truck or holder Y upwardly along the frame in a step-by-step manner to impart line spacing movements to the work sheets. This line spacing mechanism is operable when the frame X is in its forward or vertical position.

Thus prior to the line spacing operation of the work sheets, the platen has been moved rearwardly a distance sufficient to relieve the tight contact relation between the work sheets and the curved printing face of the platen 14. In other words, when the frame X is in its vertical position, the work sheets are substantially free of contact with the platen and consequently these work sheets may be line spaced without dragging the same against the platen and without dragging the transversely extending carbon strips upwardly therewith. When the frame X is in its rearwardly inclined position, the type bars are operated. In this position of the frame X, the work sheets and carbon strips are caused to tightly contact the curved printing face of the platen 14 whereby the work sheets and the carbon strips will be disposed in a compacted relation to insure clearness of print on the various sheets. Thus in one position, the work sheets are arranged in substantially flat relation for line spacing operation, and in another position these work sheets are curved about the curved printing face of the platen preparatory to printing by the type bars.

The truck or holder Y includes flat plate 22

which is positioned on the upper side of the members 8 and 9 and has downward extensions 23 and 24 respectively fitting on the outside of these channel members. This plate 22 constitutes a relatively stationary clamp bar and is provided on its under side (see Figure 7) with two brackets 25 and 26 in the depending arms of which is supported a shaft 27 which has at one end a pinion 28 meshing with a rack bar 29 on the inside of the channel bar 8. At the other end the shaft 27 has a pinion 30 meshing with a similar rack bar 31 carried by the channel member 9. The purpose of the shaft and rack 10 and pinion connections is to cause the truck Y to travel along the channel bars 8 and 9 of the frame X without binding.

Lying outside the extensions 23 and 24 and attached thereto in any desired manner, are 20 plates 32 and 33 respectively which extend upward above the surface of the plate 22. These plates are connected by a pivot shaft 34 attached thereto by screws 35 and this shaft carries a clamp member or movable 25 clamp bar 36. The work sheets are adapted to be passed between this clamp member or bar 36 and the surface of the relatively stationary clamp bar 22.

Mounted on the shaft 34 at each side, but 30 inside the plates 32 and 33, is a lever arm 37 which is normally drawn against a stop rod 38 by means of a spring 39 which is fastened at one end to the lever arm 37 and hooked at the other end over a projection 40. The rod 35 38 is provided with cam portions (see Figure 19) which bear against the arms 37 and this rod may be rocked against the tension of the spring 39 by means of handles 41. When thus rocked, it will move the clamping plate 36 away from the surface of the plate 22 and release the work sheets so that the truck Y and work sheets may be moved independently.

At the left hand side of the frame X the 45 outside flange 42 of the channel bar 9 is provided with teeth or notches in which is adapted to engage a pawl 43 pivotally supported at 44 and normally drawn to operative position by a spring 45. This pawl has 50 an upwardly extending tail 46. A similar pawl 47 is carried by the same pivot 44 and engages notches formed in a bar 48 illustrated separately in Figure 12. The function of this bar will be hereinafter described. This 55 pawl 47 also has an upwardly extending tail 49 as shown in Figure 6.

Referring to Fig. 19 there is disclosed a sliding plate 50 mounted on the side plate 33 by means of pins 51 entering slots in the plate 50. This plate has an offset ear 52 which lies outside the lever arm 37 and also a second offset ear 53 at the other end which lies outside of the tails 46 and 49 of the pawls 43 and 47. When the handles 41 are 60 moved to rock the shaft 38 and move the

lever arm 37 to release the truck Y, it is 70 obvious that the movement of this lever arm 37 will produce a sliding movement of the plate 50 through engagement with the ear 52 thereof and that in such sliding movement the ear 53 will engage the tails of the pawls 43 and 47 and move them out of operative engagement with their respective racks or notched bars. In this manner the movement 75 of the lever not only releases the truck Y from the work sheets but releases the truck from the frame so that it may be moved downward until it substantially contacts with the platen 14.

In the form of the device shown in Figure 80 6 the work sheets H are fed over the rock shaft 19 from the desired source of supply. In the preferred form of the invention shown in Figures 1 to 4, a different form of feeding 85 the work sheets is provided.

Arms 54 which are attached to the frame of the machine by the same screws which hold the feet I in position extend rearwardly and other bracket arms 55 which are attached to the top plate of the machine by 90 screws 56 extending downwardly so that the free end of each arm 54 will lie adjacent the free end of the corresponding arm 55. Screws 57 attach each pair of arms together and also are threaded into a track rail 58, 95 thus supporting the same.

A roller 59 which travels on said track rail is carried by a U-shaped bracket member 60 which is attached by a screw 61 to the generally horizontal portion 62 of a U-shaped 100 member. The upwardly extending arms 63 of this member are pivoted by screws 64 to downwardly extending arms 65 which depend from the plate member 66 (see Figure 2). This plate supports at its outer edges 105 channel shaped members 67, the open sides of which face each other and these members are provided at their upper ends with hook members 68 which engage the under side of the shaft 19. The channel members 67 and 110 the chute 4 individually and together form side edge guides for the webs and aid in holding the work sheets or forms in registration. At each side a spring 69 is attached at one end to an anchorage 70 on the member 67 and at its other end is hooked over an upward projection 71 of the arm 63. It is obvious that this spring exerts its force to hold the hook 68 in contact with the shaft 19 and the roller 59 in engagement with the track 115 rail 58. Projections 72 on the lower end of the arms 65 limit the movement of the arms 65 and 63 in one direction.

The application also discloses two different forms of mechanism for supporting the 120 carbon strips or ribbons, the preferred form being illustrated in Figures 1, 3 and 4. In this form a spindle 73 which may be an extension of the spindle which fastens the bell 125 stem in place has mounted thereon a plurality 130

of rolls of carbon strips or ribbon K. These rolls are separated by disks 74 provided with key hole slots by which they may be readily mounted upon the spindle 73.

- 5 At the left hand side of the carriage a channel shaped member 75, which opens outwardly, is attached to the side bar of the carriage by a screw 76. To the under side of this channel bar is attached an inwardly extending bracket 77 which is provided with a plurality of vertical pins 78 and each strip K is fed between a pair of said pins. Overlying the upper side of the channel bar 75 is an inwardly extending member 79 which 10 is divided at its inner end into a plurality of spring tongues 80, each of which engages a corresponding carbon strip. The bracket members 77 and 79 may be connected to the channel bar 75 by bolts 82 provided with finger nuts 83. Pins 81 extend between the two sides of the channel bar and furnish guides for the various carbon strips. Reference to Figure 4 will show that after each carbon strip K passes from beneath a spring 15 tongue 80, it is given a quarter turn so that it occupies a vertical plane and passes around its appropriate pin 81. It is then lead toward the front side of the machine and fed by mechanism which is hereinafter described.
- 20 Another form for supporting the rolls of carbon strips and placing initial and constant tension thereon is shown particularly in Figure 9. In this construction two brackets 84 attached to the side frames of the carriage 25 support a plate 85 upon which are mounted spindles 86 on which are placed the rolls of carbon. These spindles occupy a vertical position so that the carbon does not need to be given a quarter turn as in the preceding form.
- 30 After being drawn off from the roll, each strip K passes over a stationary friction pin 88. As shown in Figures 15 and 16, this pin cooperates with a second pin 89 carried by a plate 90 which is provided with an opening 35 91 through which passes the shank of a shoulder bolt 92 which supports the plate in position but permits sliding movement thereof. Each pin 88 is carried by a plate 87 which has its rear end passed through a receiving 40 slot in the rear turned-down flange of the plate 85 and its forward end secured to the plate 85 by a single shoulder bolt 92. A spring 93, connected to the plate 90 at one end and to a fixed part at the other end, normally tends to bring the pin 89 into frictional engagement with the pin 88, the carbon strip K passing between the two. This mechanism 45 is provided in connection with each carbon strip and each plate 90 has an offset ear 94 adjacent which passes a rod 95 provided with cam surfaces 96 for operating the same and corresponding in number to the maximum number of ribbons which can be employed. This rod may be operated from either side 50 of the machine by means of handles 97 so

that the pins 88 and 89 may be separated as shown in Figure 16 when it is desired to insert new carbon strips therebetween. After leaving this friction mechanism, the carbon strips pass around a common guide pin or 70 roller 98 as shown in Figure 9.

The mechanism for imposing additional frictional resistance upon the ribbons or carbon strips, for guiding them across the front of the machine and for feeding them lengthwise step-by-step is the same in both forms 75 of the carbon strip supporting means and will now be described with particular reference to Figures 9, 13, 14, and 17.

After the carbon strips pass the guide roller 80 98 of Figure 9 or the guide pins 81 of Figure 4, they pass through mechanism which is adapted for imposing additional frictional resistance thereupon as desired. A channel bar 99 is fastened to the side plates B of the carriage by a pin 100, but is spaced therefrom by a spacing block 101. Mounted within the channel is a spring 102 which is fastened to the bottom of the channel bar by a screw 103 and is bent on itself so that its free end will bear against a projecting portion 104. Carbon strips K pass between the projection 104 and the free end of the spring 102. A cam member 105 is mounted on a pivot 106 and is carried by a lever 107 which is pivoted at 108 95 to a link 109. When this link is operated as hereinafter described, the cam 105 will be turned to contact the spring 102 and press the free end of said spring against the carbon strips, thus imposing additional resistance 100 thereon.

This additional resistance is not intended to be very great and is only imposed at certain times as hereinafter described, and in some respects a modified form of this portion of the mechanism shown in Figure 10 is found preferable. In this modified construction instead of the spring 102 there is provided a spring 110 attached to the channel bar by a screw 111 and having a free end 112. This spring is bowed slightly intermediate its ends and the bent portion is intended to press the carbon strip K against the projection 104. The lever 107 together with the cam 105 is the same as in the other form, but instead of the link 109 one end of a coil spring 113 is attached to the lever 107, the other end of the spring being attached to an operating mechanism hereinafter described. It may also be noted that in the form shown in Figure 9, the spring 113 may be substituted for the link 109.

The additional frictional resistance imposed by either of these mechanisms upon the carbon strips is not intended to be sufficient to prevent endwise movement of the ribbon against force such as would be exerted by the carbon strip feeding mechanism, but merely to prevent any accidental displacement during certain phases of the operation 130

of the machine which will be described hereafter.

After passing the mechanism just described, the carbon strips K pass around a guide roller 114 at the left hand side of the machine across the front of the platen where they will be interleaved with the work sheets, around a guide roller 115 carried by a channel bar 116 at the right hand side of the carriage, and rearward to feeding mechanism which will now be described. The channel bar 116 is fastened to the side plates B of the carriage by a screw 117, a spacing block 118 being interposed to space the two parts. The carbon strips K now pass between two corrugated rollers or gears 119 and 120. The gear or roller 119 is the feeding member and is given its motion by a detent 121 normally held in engagement with the roller by a spring 122. A holding detent 123 is also normally held by a spring 124 in contact with the roller 119 to prevent reverse movement of the same. The feeding detent 121 is carried by a forwardly extending link 125 which is given its feeding movement by means hereinafter described.

It is desirable that the rollers 119 and 120 be pressed against each other with considerable force and also that they may be separated for the purpose of feeding in fresh carbon strips. To attain this result the following construction is employed. As clearly shown in Figure 17, the roller 119 is pivotally mounted in the sides of the channel bar 116. The roller 120 is mounted on a spindle 126 provided with a finger piece 126' and this spindle is mounted in the sides of a U-shaped frame 127 which fits over the channel bar 116. A rod having a cam 128 thereon is mounted in the U-shaped frame 127 and is provided with a handle 129. When this rod is turned, the cam engages a bracket 130 which is fixed to the channel bar 116 as clearly shown in Figure 13, and therefore moves the whole U-shaped frame toward the right in Figures 13 and 17, thereby moving the roller 120 out of engagement with the roller 119. This movement is in opposition to a flat spring 131 which is fastened to the side frame B of the carriage by a screw 132 and is attached to the U-shaped frame 127 by fastening means 133 and normally tends to move this frame toward the left in Figures 13 and 17. The U-shaped frame is guided in its sliding movement by lugs 134 and 135 fixed to the channel bar 116.

As stated above, a step-by-step movement of the truck or holder Y relative to the frame X, for the purpose of giving line space movement to the work sheets, is brought about by moving the notched bar 48. This bar has lugs 136 at each side thereof, the lugs on one side contacting with the rack bar 31, and the lugs on the other side with

the outside wall of the channel bar 9 as shown in Figure 7. These lugs guide the notched bar in its to and fro movement. The free end thereof is provided with a notch 137 which fits over a pin (not shown) extending between the walls of the channel bar 9. A spring 138 is attached at one end to the bar 48 and at its other end to a fixed part 139 and serves to return the bar after the upward movement thereof. To the lower end of the bar 48 a short rack 140 is pivoted at 141 and is normally maintained in one position by a spring 142 attached off center to the rack at one end and at its other end to the bar 48. This rack 140 meshes with a pinion 143 carried on one end of a short sleeve 144 which is loosely mounted on the platen shaft 1. It will be obvious that when the pinion 143 is rotated, it will give an upward movement to the bar 48 and the engagement of the notches of this bar 48 with the pawl 47 will move the truck or holder Y upward one line space distance. The truck will then be retained in its new position by the pawl 43 and the spring 138 will act to return the notched bar 48 to its starting point.

The link 125 which, as explained above, is moved for the purpose of feeding the ribbons, is connected at its free end to one arm of a bell crank lever 145 which is pivoted at 146 to the channel bar 116. The other arm of this bell crank is provided with a slot 147 in which may be adjusted a pin 148 which is carried by a small U-shaped member 149. A link 150 is connected to the pin 148 and it is obvious that an adjustment of this pin in the slot toward and from the pivot 146 of the bell crank lever will vary the amount of movement given to the link 125 and, therefore, the extent of feeding movement of the ribbon or carbon strips. This link 150 extends to the left hand side of the machine and is connected to one arm 151 of a bell crank lever pivoted at 152 to a bracket arm 153 extending from the carriage frame. The other arm 154 of this bell crank lever is pivoted at 155 to a link 156 which is provided at one side with a short rack 157 which meshes with a pinion 158 on the sleeve 144 above mentioned.

The arm 21 best shown in Figure 6, which extends from the rock shaft 19, is pivoted at its free end at 159 to a forwardly extending link 160. When this link is moved rearwardly, the arm 21 rocks the shaft 19 and moves the arms 18 and 16 as well as the frame to the dotted line position of Figure 6, in which the sheet supporting frame is substantially vertical. At the same time the pivot point 7 of the frame and the arm 6 moves slightly to the rear, being guided by engagement of the slot 13 with the platen axle 1 so that the platen moves slightly away from the work sheets H. The relative position of the

work sheets and platen is illustrated in Figure 8.

It is obvious from the above description that a pull on the link 109 or the spring connection 113 in the modification of Figure 10 will place additional frictional resistance upon the carbon strips. A rearward movement of the link 160 will move the frame supporting the work sheets from the full to the dotted line position of Figure 6. A rearward movement of the link 156 will rotate the pinion 158 and sleeve 144, thereby rotating the pinion 143 and line spacing the work sheets. At the same time this rearward movement of the link 156 through the bell crank lever and connection 150 to the opposite side of the machine will feed the ribbons a short distance lengthwise. The construction by which these various operations are performed in the proper sequence will now be described.

This operating mechanism will be described with special reference to Figures 5, 9, 11, and 18. A flat cam member 161 is pivotally supported at 162 upon a bracket 163 extending from one side bar of the carriage. Fastened to the cam 161 by a screw 164 is a lever 165 which corresponds in general location and shape to the usual carriage return lever of a typewriting machine. Three levers 166, 167, and 168, shown separately in Figure 18, are pivoted at 169 upon an extension of the bracket 163. This pivot pin 169 passes through an opening 170 in one end of the lever 166, an opening 171 in one end of the lever 167, and an opening 172 in the lever 168 which is a bell crank lever. One arm 173 of this bell crank lever has a roller 174 which normally engages the portion 175 of the cam 161. When the lever 165 is operated by movement to the right and the cam 161 rotated, the first movement thereof rocks the bell crank 168 and pulls on the link 109 or the spring connection 113, in Figure 10, which link or spring is connected to the arm 177 of the bell crank lever 168 at 178. This pull will impose the additional frictional resistance upon the carbon strips or ribbon.

During movement of the lever 165 to the right a cam portion 179 which is in engagement with a roller 180 carried by the lever 166, will swing this lever rearwardly and since the outer end thereof is connected at 181 to the link 160, this movement will swing the frame forwardly from its normal rearwardly inclined position to the substantially vertical or dotted line position of Figure 6. At this time the cam 161 is in the full line position of Figures 9 and 21 and the lever 166 is in the dotted line position of said Figure 9 in full line position in Figure 21.

A continued movement of the lever 165 in the same direction will cause the roller 174 to move down the surface 182 of the cam 161 and release the additional frictional resist-

ance which has been placed upon the carbon strips or ribbons. During this continued movement, the roller 180 rides on the surface 183 of the cam which is concentric with the pivotal center thereof and, therefore, the frame is held in its vertical position.

Shortly after the cam passes from the position shown in Figures 9 and 21, a roller 184 carried by the under side of the cam 161 will move in the direction shown by the arrows in said figure and engage the lever 167 as shown in Figure 22. This lever is pivoted at 185 to the link 156 and the movement of this lever will, therefore, through the rack 157, pinion 158, sleeve 144, and pinion 143, operate to line space the truck Y. During this period of line spacing, the roller 180 engages the concentric peripheral portion 183 of the cam 161, to maintain the frame X in its vertical position. At the same time the movement of the link 156 through the bell crank 154 and connections will operate to give the carbon strips or ribbons a short endwise or feeding movement.

Immediately following these operations the carriage will be returned to the right hand side of the machine and upon return of the lever to its initial position the work sheets will be in position to begin a new line of writing.

In loading the machine with the work sheets and carbon strips preparatory to writing operations, the pack from which the continuous web of forms or work sheets are supplied, is positioned upon a suitable support at the rear of the machine as shown in Figure 1. The leading end of the web is then fed upwardly and forwardly through the channel guide members 67, then forwardly over the shaft 19, then downwardly and forwardly over the table G, thence upwardly through the guide chute 4 to a point somewhat above the printing line across the platen 14. The members 67 and the chute 4 constitute side edge guides for the webs.

The operator, taking note of the number of copies that are to be made, next feeds off the free ends of carbon strips from a suitable number of spools, the usual typewriter ribbon being disposed in front of the work sheets for cooperation with the foremost one thereof. These free strip ends, after being fed individually through the constant tension applying devices 88, 89 are collectively passed about the guide roller 98 and threaded through the additional tension applying devices 102, 104, after which said ends are drawn forwardly and turned about the guide roller 114 at the front left hand corner of the machine. At this time the frame X is in its normal rearwardly inclined position and the additional tension device 102, 104 is in its normal or ineffective position.

The free ends of the carbon strips are pulled forwardly a sufficient distance and are next

interleaved with the leading ends of the superposed work sheets comprising the form web and which portions extend above the chute 4, one carbon strip being placed between each adjacent pair of such sheets. The free ends of the carbon strips are then turned about the guide roller 115 at the right hand front corner of the machine and thence rearwardly along the right hand side of the machine toward the rear where they are placed between the feed rollers 119 and 120 which have previously been forced apart by manipulation of the cam lever 129 and which are thereafter released to cause them to operatively engage the carbon strip ends between them.

By moving the lever 165 from the position shown in Figure 11 to the position shown in Figures 9 and 21, the frame will be moved to the substantially vertical position shown in dotted lines in Figure 6 and for causing the devices 102, 104 to grip the carbon strips for the purpose of applying additional tension thereto for the purpose of holding said carbon strips taut across the printing line.

At this time the truck Y will be supported upon the frame X a suitable distance above the leading ends of the work sheets. The operator may now grasp the work sheets at their leading ends above and free of the carbon strips and pull them upwardly toward the truck. The carbon strips being taut by reason of the application of additional tension devices 102, 104, will be held against any tendency of being dragged upwardly with the work sheets during this period, and in view of the flat relation of the work sheets and the substantially vertical direction of pull, all frictional engagement between work sheets and carbon sheets, that would tend to smut or smear said work sheets is effectively avoided.

While holding the leading end of the web in her grasp, the operator actuates the lever 41 of the truck to release said truck from connection with the line spacing mechanism, and to separate the stationary and movable clamping members 22 and 36 of the truck. The truck thus released may be conveniently supported upon the hands of the operator while the leading end of the web is moved upwardly by the operator through a suitable distance beyond the clamping members 22 and 36 where the web will be again grasped by the operator after which the truck is freely lowered to its lowermost or starting position. The web is then adjusted longitudinally so that the clamping member 36 will engage the web at the line dividing the first and second forms of the web, after which the lever 41 is moved to cause the clamping member 36 to securely clamp the web against the member 22. The form above the truck is negligible waste and may be torn off, using the clamping member 36 as a straight edge for

that purpose. The first form is now in position wherein the first line thereof is in registration with the printing line of the platen.

The lever 165 is then returned to its initial position as shown in Figure 11, the additional tension on the carbon strips being released and the frame X being returned to its normal rearwardly inclined position as shown in full lines in Figure 6. The work sheets and interleaved carbon strips will, by this return movement of the frame, be changed from their previous vertical flat and loose condition to an arcuate and tightly compacted condition in engagement with the platen at the printing line. The machine is now ready for writing operations.

The first line will then be written on the form in the usual manner. It then becomes necessary to line space the work sheets so that the next succeeding line of the first form may be written.

To this end the operator swings the lever 165 forwardly and toward the right. The first part of this movement will cause the appropriate surfaces of the cam 161 (see Figure 20) to engage the rollers 174 and 180 to impart a pull on the link 109 and a thrust on the link 160 to impose the additional tension upon the carbon strips and to swing the frame X forwardly to the vertical position respectively. Thus when the lever 165 has been moved to the position shown in Figures 9 and 21, the frame will be positioned vertically and the carbon strips will be held taut across the printing line, the parts being retained in this position by reason of the engagement of the roller 174 with the shallow retaining seat 176 of the cam 161. It will be recalled that each forward movement of the frame X from its normal inclined position to the vertical is attended by a rearward movement of the platen away from tight compacting engagement with the work sheets and carbon strips, and that when the frame is vertical the work sheets will therefore be disposed loose and substantially vertical and flat in front of the platen.

After the frame has reached the vertical, the continued movement of the lever 165 toward the right will cause the roller 174 to ride down the cam surface 182 and thus release the additional tension, after which the roller 184 engages the lever 167 to effect line spacing of the work sheets and endwise movement of the carbon strips. Immediately after the completion of these movements of the lever 165, continued pressure on the lever toward the right effects return of the carriage, all of the operations which are independently effected by the lever taking place during the single hand engagement with such lever that is customarily employed to return the carriage in the ordinary machine.

During the line spacing and carbon strip feed effecting movement of the lever 165 the

frame is retained in the vertical position since the roller 180 will ride on the concentric surface 183 of the cam 161.

It should be understood that the carbon strips are fed a short distance only at each feeding interval, for example one-sixteenth of an inch. This feed distance may be varied by use of the devices 147, 148, 149, and when the carbon strips finally pass out between the feed rollers 119 and 120 they are exhausted and may be torn off and thrown away.

Carbon strips of this character sufficient to write a very large number of forms may be mounted in either of the forms shown in a very compact condition. In the preferred form they are carried by the machine frame (see Figures 1 and 3) and therefore they do not impose any added weight or resistance to the movement of the carriage. Even when carried by the carriage they add a relatively small amount of weight and do not interfere with the easy operation of the machine.

As each line of the form being written is completed, the lever movement above described is repeated to effect line spacing, ribbon feed and carriage return.

When the form has been completed the truck Y will have reached an elevated position, such as is shown in Figure 6. The lever 165 is then moved to the position shown in Figures 9 and 21 to bring the frame X to the vertical position and to impose the additional tension upon the carbon strips to hold them taut in their interleaved relation with the now loose and substantially flat work sheets.

Proper actuation of the lever 41 will release the clamp 36 from the work sheets and also release the pawls of the line spacing mechanism from engagement with the toothed parts 42 and 48 with which they cooperate whereupon the truck Y may be moved downwardly to its lowest position, during which movement the leading end of the work sheets will be held by hand.

The completed form is then pulled upwardly through the truck clamp a sufficient distance to bring the bottom thereof into register with the clamp bar 36. The clamp bar 36 is then caused to press tightly against the line separating the completed form from the form next succeeding so that said bar can be used as a tearing edge to facilitate the removal of the completed form. Upon return of the lever 165 to its normal position the frame X and the carriage will likewise be returned to their normal positions and the machine parts will then be in position to begin writing on the next form, no additional manipulation being necessary to bring the carbon strips into proper relation with the work sheets or platen.

It will be understood that each time the work sheets are line spaced or otherwise moved, the frame X is first moved to the ver-

tical position to relieve the normal curved and compacted condition of the work sheets and interleaved carbon strips at the printing line, and to dispose the work sheets in a loose, vertical and flat condition to enable the line spacing movement of the work sheets, as well as the carbon strip feed movement, to take place without danger of the carbon strips being dragged upwardly and out of position by the work sheets or the work sheets smutted or smeared by tight frictional engagement with said carbon strips.

There may be combined with the invention thus far described a separate record work sheet for use in what is frequently known as condensed billing. This work sheet L will be fed around the platen through a separate chute 186 so that adjustment of the continuous work sheets may be obtained without displacement of the record sheet.

This sheet is generally wider than the continuous sheets and contains information which is not printed upon the continuous sheets. The printing on the record sheet outside the margins of the continuous sheets will be directly through the carbon strips so that the entire record on the record sheet will be a carbon copy.

The leading end of the record sheet is clamped in position by the same clamp which holds the leading end of the continuous work sheets. After a bill or form has been written, the paper clamp is released and dropped as previously described. Thereafter the continuous sheets will be pulled through the machine a short distance in order to permit the first bill to be drawn off. This movement does not disturb the record sheet. Therefore, when the second bill is written in the usual manner, the first line of writing thereon will be recorded on the record sheet on the very next line from the last line of the previously written bill. A condensed record is, therefore, obtained. When the record sheet is filled, a second sheet can be inserted in the usual manner after the first is removed by releasing the clamp therefrom.

Various features of the invention are broader than the specific form illustrated. Instead of returning the carriage and performing the other operations by a manually operated lever, the same might be operated by power mechanism. Also while the specific form of carbon strip feeding mechanism is illustrated as a pair of corrugated rolls between which all strips pass, it would, of course, be possible to provide a separate pair of feeding rolls for each carbon strip, in which case smooth feeding rolls would be satisfactory.

Numerous advantages flow from the use of the various mechanisms above described in the way of ease and efficiency of operation, and the economies effected by savings

in labor and materials incident to such operation, some of which advantages are enumerated below and other of which will be obvious to those skilled in the art.

• The substitution of carbon strips or ribbons for the customary carbon paper sheets and the use of a vertically-travelling paper truck which pulls the forms up past the printing line bring about obvious advantages. They include the complete elimination of carbon handling for from 1000 to 5000 forms, depending upon how many are included in a pack—an economy amounting to anywhere from 30 to 50% in carbon paper 70 cost—perfect lateral and vertical registration of forms,—and considerable saving of time in the writing of bills or forms over previously known methods.

The machine is capable of making good, 20 clear, legible carbon copies automatically at all times—whether it is the first or the thousandth form written—without any effort or attention on the part of the operator. Every carbon copy written will be clear and 25 legible and no mistakes will occur due to poor legibility.

The machine herein described feeds both 30 the form and the carbon automatically. When the operator has torn off the form just written, the next new form is at the first writing line and absolutely no time or effort is expended on fussing with carbon paper sheets. With the usual preparatory work thus done away with, the writing of 35 any form is reduced to an ordinary typing operation.

With every actuation of the line space handle the carbon strips are fed across the printing line a fixed distance, say from $\frac{1}{16}$ th of 40 an inch to $\frac{1}{8}$ ths of an inch depending on the feed adjustment. Therefore, any spot on the carbon strips will be called upon to make as many impressions as $\frac{1}{16}$ th of an inch or $\frac{1}{8}$ ths of an inch will divide into the width 45 of the form used.

The automatic feed of the carbon strips relieves the operator of the continual mental effort of deciding whether another set of forms can be written or not with the carbon sheets just used without getting into difficulties in one or two ways; that of throwing the carbon paper away before it is entirely used up and being wasteful, or of using it too long and allowing the work to become illegible.

For the best carbon copies, it is necessary to have all the parts of the form and the several carbon strips in as close a pack as possible at the writing point, so that the 50 force of the blow of the type bar will carry through to the last copy with a light staccato blow. This is not possible with ordinary typewriter construction, because there must be room between the platen and the writing line for the form to be fed upwardly,

otherwise the form will bind. In the machine herein described, however, when the form is fed upwardly, the platen is first backed away from the writing line giving the form plenty of room to be fed either upward or backward; but when the machine is ready to write, the platen and the form are actually pushed right up against the writing point, thus compacting the superposed form sheets and interleaved carbon strips 75 at the writing line. This construction will even iron out any air pockets that sometimes form with use of carbon sheets.

Thus by using carbon strips which are fed automatically, and by the use of an oscillating platen, the machine presents the ideal condition under which to make carbon copies 80 without any effort or attention on the part of the operator.

The novel mechanisms employed in the 85 machine for feeding the forms, also bring about notable advantages in the way of visibility and the assurance that the superposed forms will always remain in perfect registration.

Full view of the progress of the work is desirable in ordinary typewriting and is an absolute essential in form writing. With the typewriter the operator writes an unbroken line straight across the paper and, to see 95 if it is correct, looks only at the finished line. Writing forms, though, is an altogether different proposition. The typing here is not in an unbroken line. If it is an invoice form, there are usually a number of items to fill 100 in very definite and particular spaces in the form. There may be definite and particular columns in which to fill certain figures. If the operator has not her work visible and cannot see exactly what she is writing, she 105 is very apt to write in the wrong place or column. Supporting the form web upon a flat frame and effecting line space movement thereof by a truck which clamps the leading edges thereof, assures perfect visibility of the whole of the written portion of a form as the form is being written.

In the use of continuous or web forms it 115 is very important to secure good registration. By this is meant the ability to write on the same relative line on each part of the form. This is very essential, especially on ruled bills of lading, for the reason that very often the various items of the bill are printed on a form and only the quantity and cost are filled in by the machine. It will be readily understood that if the same line is not filled in on each part of the form, the first part of the form will designate one item and the last part of the form will designate an entirely different item. This will actually happen if the machine used to do the typing does not give good registration.

The herein described machine eliminates 120 the cylinder and feed roll method of feed-

ing and consequently is free from the disadvantages occasioned by variations in work thicknesses and combined platen and work diameters and the creeping and slippage 5 commonly dealt with in machines which employ such feeding instrumentalities. In my improved machine the work sheets are drawn forwardly and upwardly over the frame and past the printing line by a truck that is fed 10 step-by-step through proper line space distances and which has thereon a clamp to grip the leading ends of said sheets. The tight clamping of the leading sheet ends and the substantially flat travel of said sheets 15 assures perfect registration at all times without the aid of side clamps or registering hooks or pins operating through necessarily perforated form sheets. The employment 20 of web side clamps and other types of such registration effecting devices requires the expenditure of additional unnecessary labor in form typing operations, and on this point alone the herein-described machine materially increases the potential output of 25 work.

It is to be noted that various features of the invention are capable of use in different relations and that they are not limited in their application to any specific type of machine. So far as the feeding movement of the work sheets and carbon strips is concerned, it is entirely immaterial whether the carriage has letter space movement or whether type mechanism is movable relatively to 30 said work sheets. This portion of the invention might also be used in manifolding apparatus in which the writing is performed manually. It is also to be noted that various features of the invention may be modified 35 widely and that the present construction is to be regarded as illustrative and not as limiting the scope of the invention.

I claim as my invention:

1. A manifolding device comprising a 45 platen past which work sheets are fed, means for supporting a plurality of carbon strips interleaved with and transverse to said work sheets, means independent of the platen for line spacing the work sheets, means for 50 feeding the carbon strips, and a single manually operable independent element for controlling both of said means.

2. A manifolding device comprising a 55 platen past which work sheets are fed, a frame over which said work sheets travel in their line space movement, means for supporting a plurality of carbon strips interleaved with said work sheets, said frame being normally inclined rearwardly to tightly 60 compact the work sheets and carbon strips with the platen, means for swinging said frame to a vertical position preliminary to the line space movement to relieve said tight compact relation between the work sheets and the carbon strips, means for line spacing the 65 work sheets while the frame is in said vertical position, means for feeding the carbon strips,

ing said work sheets while the frame is in vertical position.

3. A manifolding device comprising a platen past which work sheets are fed, a frame over which said work sheets travel in 70 their line space movement, means for supporting a plurality of carbon strips interleaved with said work sheets, said frame being normally inclined rearwardly to tightly compact the work sheets and carbon strips with the platen, means for swinging said frame to a vertical position preliminary to the line space movement to relieve said tight compact relation between the work sheets and the carbon strips, and means independent 75 of the platen for line spacing the work sheets while the frame is in said vertical position.

4. A manifolding device comprising a platen past which work sheets are fed, a frame over which said work sheets travel in their line space movement, means for supporting a plurality of carbon strips interleaved with said work sheets, said frame being normally inclined rearwardly to tightly 80 compact the work sheets and carbon strips with the platen, means for swinging said frame to a vertical position preliminary to the line space movement to relieve said tight compact relation between the work sheets and the carbon strips, and means for feeding 85 the carbon strips while said tight compact relation between the work sheets and carbon strips is relieved.

5. A manifolding device comprising a 90 platen past which work sheets are fed, a frame over which said work sheets travel in their line space movement, means for supporting a plurality of carbon strips interleaved with said work sheets, said frame being normally inclined rearwardly to tightly 95 compact the work sheets and carbon strips with the platen, means for swinging said frame to a vertical position preliminary to the line space movement to relieve said tight compact relation between the work sheets and the carbon strips, means for line spacing the work sheets while the frame is in said vertical position, and means for feeding the carbon strips.

6. A manifolding device comprising a 100 platen past which work sheets are fed, a frame over which said work sheets travel in their line space movement, means for supporting a plurality of carbon strips interleaved with said work sheets, said frame being normally inclined rearwardly to tightly 105 compact the work sheets and carbon strips with the platen, means for swinging said frame to a vertical position preliminary to the line space movement to relieve said tight compact relation between the work sheets and the carbon strips, means for line spacing the work sheets while the frame is in said vertical position, means for feeding the carbon strips,

and a single element for operating the last three means.

7. A manifolding device comprising a platen past which work sheets are fed, a frame over which the work sheets travel in their line space movement, means for supporting a plurality of carbon strips interleaved with the work sheets, said frame being normally inclined rearwardly to tightly compact the work sheets and carbon strips with the platen, means for swinging the frame to a vertical position and moving the platen out of contact with the sheets to relieve said tight compact relation of the work sheets during the line space movement, and means for line spacing the work sheets while the frame is in said vertical position.

8. A manifolding device comprising a platen past which work sheets are fed, a frame over which the work sheets travel in their line space movement, means for supporting a plurality of carbon strips interleaved with the work sheets, said frame being normally inclined rearwardly to tightly compact the work sheets and carbon strips with the platen, means for swinging the frame to a vertical position and moving the platen out of contact with the sheets to relieve said tight compact relation of the work sheets during the line space movement, and means independent of the platen for line spacing the work sheets while said frame is in said vertical position.

9. A manifolding device comprising a platen past which work sheets are fed, a frame over which the work sheets travel in their line space movement, means for supporting a plurality of carbon strips interleaved with the work sheets, said frame being normally inclined rearwardly to tightly compact the work sheets and carbon strips with the platen, means for swinging the frame to a vertical position and moving the platen out of contact with the sheets to relieve said tight compact relation of the work sheets during the line space movement, and means for feeding the carbon strips while said tight compact relation between the work sheets and carbon strips is relieved.

10. A manifolding device comprising a platen past which work sheets are fed, a frame over which the work sheets travel in their line space movement, means for supporting a plurality of carbon strips interleaved with the work sheets, said frame being normally inclined rearwardly to tightly compact the work sheets and carbon strips with the platen, means for swinging the frame to a vertical position and moving the platen out of contact with the sheets to relieve said tight compact relation of the work sheets during the line space movement, means for line spacing the work sheets while the frame is in said vertical position, and means for feeding the carbon strips.

11. A manifolding device comprising a platen past which work sheets are fed, a frame over which the work sheets travel in their line space movement, means for supporting a plurality of carbon strips interleaved with the work sheets, said frame being normally inclined rearwardly to tightly compact the work sheets and carbon strips with the platen, means for swinging the frame to a vertical position and moving the platen out of contact with the sheets to relieve said tight compact relation of the work sheets during the line space movement, means for line spacing the work sheets while the frame is in said vertical position, means for feeding the carbon strips, and a single manually controlled element for operating the last three means.

12. A manifolding device comprising a pivoted platen past which work sheets are fed, a guide for said sheets below the platen, line space mechanism including movable holding means for the leading ends of the sheets, means for supporting a plurality of carbon strips lengthwise of the platen and interleaved with the work sheets, said guide, said holder and said platen being correlative disposed to normally hold said sheets and carbon strips tightly compacted against the platen, and means for swinging the platen and moving the holder to relieve said tight compact relation of the sheets and carbon strips when line spacing.

13. A manifolding device comprising a pivoted platen past which work sheets are fed, a guide for said sheets below the platen, line space mechanism including movable holding means for the leading ends of the sheets, means for supporting a plurality of carbon strips lengthwise of the platen and interleaved with the work sheets, said guide, said holder and said platen being correlative disposed to normally hold said sheets and carbon strips tightly compacted against the platen, means for swinging the platen and moving the holder to relieve said tight compact relation of the sheets and carbon strips when line spacing, and means for line spacing the work sheets and feeding the carbon strips while the work sheets and platen are relieved of said tight compact relation.

14. A manifolding device comprising a platen past which work sheets are fed, means for supporting a plurality of carbon strips interleaved with said work sheets, means for swinging said sheets to a vertical position preliminary to line spacing, and normally inoperative means for imposing a frictional resistance to the movement of the carbon strips while said sheets are being swung.

15. A manifolding device comprising a platen past which work sheets are fed, an inclined frame over which said sheets travel in their line space movement, means for supporting a plurality of carbon strips inter-

- leaved with said work sheets, means for swinging said frame to a vertical position, and normally inoperative means for imposing a frictional resistance to the movement of the carbon strips while said frame is being swung. 5
16. A manifolding device comprising a platen past which work sheets are fed, an inclined frame over which said sheets travel in their line space movement, said frame being supported for swinging movement, means for supporting a plurality of carbon strips interleaved with said work sheets, and manually controlled means for imposing a frictional resistance to the movement of the carbon strips and swinging said frame to a vertical position. 10
17. A manifolding device comprising a platen past which work sheets are fed, an inclined frame over which said sheets travel in their line space movement, said frame being supported for swinging movement, means for supporting a plurality of carbon strips interleaved with said work sheets, and manually controlled means, the operation of which imposes a frictional resistance to the movement of the carbon strips and swings said frame to vertical position, and then releases said frictional resistance. 20
18. A manifolding device comprising a platen past which work sheets are fed, an inclined frame over which said sheets travel in their line space movement, said frame being supported for swinging movement, means for supporting a plurality of carbon strips interleaved with said work sheets, and manually controlled means, the operation of which imposes a frictional resistance to the movement of the carbon strips then swings said frame to vertical position, and releases said frictional resistance, and then line spaces the work sheets and feeds the carbon strips lengthwise. 30
19. A manifolding device comprising a platen over which travels a plurality of work sheets, means for supporting a plurality of carbon strips along the printing line of the platen and interleaved with the work sheets, a shaft, two pinions on said shaft which rotate in unison, connections operated by one pinion for line spacing the work sheets, means for operating the other pinion, and connections from said pinion operating means for feeding the carbon strips lengthwise. 40
20. In a manifolding device having means for supporting a plurality of work sheets and a plurality of carbon strips interleaved therewith over the printing line, a feeding device for the carbon strips located at one side of the machine and comprising two corrugated rolls between which pass all the strips, a driving pawl for one roll, a holding pawl, and means located at the other side of the machine for operating the driving pawl. 50
21. In a manifolding device having means for supporting a plurality of work sheets for line space movement and a plurality of carbon strips interleaved therewith over the printing line, a pair of corrugated rolls located at one side of the machine through which all said strips pass, a driving pawl for engaging one roll, means for driving said pawl, and means for line spacing the work sheets at the same time. 70
22. A manifolding device comprising printing mechanism as one element, a frame for supporting a plurality of work sheets as another element and including a platen, said elements being mounted for relative movement for letter spacing, means for supporting a plurality of carbon strips interleaved with said work sheets, and a single manually operable device for effecting a relative return movement between said elements, separating the work sheets and platen, line spacing said work sheets, and feeding said strips. 75
23. A manifolding device comprising printing mechanism as one element, an inclined frame for supporting a plurality of work sheets as another element said frame being movable to vertical position, said elements being mounted for relative movement for letter spacing, means for supporting a plurality of carbon strips interleaved with said work sheets, and a single manually operable device for swinging said frame to a vertical position, effecting a relative return movement between said elements, and line spacing said work sheets. 80
24. A manifolding device comprising printing mechanism as one element, an inclined frame for supporting a plurality of work sheets as another element said frame being movable to vertical position, said elements being mounted for relative movement for letter spacing, means for supporting a plurality of carbon strips interleaved with said work sheets, and a single manually operable device for swinging said frame to a vertical position, effecting a relative return movement between said elements, line spacing 90
- 100 said work sheets, and feeding said strips. 105
25. A manifolding device comprising a travelling carriage, an inclined frame pivoted thereon for supporting a plurality of work sheets, means for supporting a plurality of carbon strips interleaved with said work sheets, a manually operable member carried by one side of the carriage frame, and means operated by said member for swinging the pivoted frame to a vertical position and thereafter line spacing said work sheets. 115
26. A manifolding device comprising a travelling carriage, an inclined frame pivoted thereon for supporting a plurality of work sheets, means for supporting a plurality of carbon strips interleaved with said work sheets, a manually operable member carried by one side of the carriage frame, and means operated by said member for swinging the 120
- 125
- 130

pivoted frame to a vertical position and thereafter line spacing said work sheets and feeding said strips endwise.

27. A manifolding device comprising a travelling carriage, an inclined frame pivoted thereon for supporting a plurality of work sheets, means for supporting a plurality of carbon strips interleaved with said work sheets, a carriage return lever, and means operated by said carriage return lever for swinging the frame to a vertical position and thereafter line spacing said work sheets.

28. A manifolding device comprising a travelling carriage, an inclined frame pivoted thereon for supporting a plurality of work sheets, means for supporting a plurality of carbon strips interleaved with said work sheets, a carriage return lever, and means operated by said carriage return lever for swinging the frame to a vertical position and thereafter line spacing said work sheets and feeding said strips endwise.

29. A manifolding device comprising a travelling carriage, an inclined frame pivoted thereon for supporting a plurality of work sheets, means for supporting a plurality of carbon strips interleaved with said work sheets, a carriage return lever, and means operated by said carriage return lever for swinging the frame to a vertical position and thereafter line spacing said work sheets and feeding said strips endwise, all said operations being performed by a continuous movement of said lever in one direction.

30. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for swinging said frame to a vertical position and said platen slightly away from said work sheets.

31. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for swinging said frame to a vertical position and thereafter line spacing said work sheets.

32. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for placing a frictional resistance upon said strips

and swinging the frame to a vertical position.

33. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for placing a frictional resistance upon said strips and swinging the frame to a vertical position, and then line spacing the work sheets.

34. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for placing a frictional resistance upon said strips and swinging the frame to a vertical position, releasing said resistance and then line spacing the work sheets and feeding the strips lengthwise.

35. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for swinging the frame to a vertical position and the platen slightly away from the work sheets to prevent binding between the work sheets and strips, and thereafter line spacing the sheets and feeding the strips lengthwise.

36. A manifolding device comprising a travelling carriage, an inclined frame pivoted thereon for supporting a plurality of work sheets, a platen carried by said frame, means for supporting a plurality of carbon strips interleaved with said work sheets, a manually operable member on said carriage, and means operated by said member for placing a frictional resistance upon said strips and swinging the frame to a vertical position, releasing said resistance and then line spacing the work sheets and feeding the strips lengthwise, all said operations being performed by a continuous movement of said member in one direction.

37. A manifolding device comprising a travelling carriage, an inclined frame pivoted thereon for supporting a plurality of work sheets, a platen carried by said frame, means for supporting a plurality of carbon strips interleaved with said work sheets, a carriage return lever, and means operated by the carriage return lever for swinging the frame to a vertical position and moving said platen slightly away from said work sheets.

38. A manifolding device comprising a

travelling carriage, an inclined frame pivoted thereon for supporting a plurality of work sheets, a platen carried by said frame, means for supporting a plurality of carbon strips interleaved with said work sheets, a carriage return lever, and means operated by the carriage return lever for swinging the frame to a vertical position and moving said platen slightly away from said work sheets and thereafter line spacing the work sheets, said operations being performed by moving said lever in a direction to return the carriage.

39. A manifolding device comprising a travelling carriage, an inclined frame pivoted thereon for supporting a plurality of work sheets, a platen carried by said frame, means for supporting a plurality of carbon strips interleaved with said work sheets, a carriage return lever, and means operated by the carriage return lever for swinging the frame to a vertical position and moving said platen slightly away from the work sheets and thereafter line spacing the work sheets and feeding the strips lengthwise, said operations being performed by moving the lever in a direction to return the carriage.

40. A manifolding device comprising a travelling carriage, a non-rotatable platen supported thereon, means for supporting a plurality of work sheets over said platen, means for supporting a plurality of carbon strips interleaved with said work sheets, a carriage return lever, and means operated by said carriage return lever for moving the platen away from the work sheets.

41. A manifolding device comprising a travelling carriage, a non-rotatable platen supported thereon, means for supporting a plurality of work sheets over said platen, means for supporting a plurality of carbon strips interleaved with said work sheets, a carriage return lever, and means operated by said carriage return lever for imposing a frictional resistance upon said strips and moving the platen away from the work sheets.

42. A manifolding device comprising a travelling carriage, a non-rotatable platen supported thereon, means for supporting a plurality of work sheets over said platen, means for supporting a plurality of carbon strips interleaved with said work sheets, a carriage return lever, and means operated by the carriage return lever for imposing a frictional resistance upon said strips and moving the platen away from the work sheets, and then line spacing said sheets.

43. A manifolding device comprising a travelling carriage, a non-rotatable platen supported thereon, means for supporting a plurality of work sheets over said platen, means for supporting a plurality of carbon strips interleaved with said work sheets, a carriage return lever, and means operated by the carriage return lever for imposing a frictional resistance upon said strips and moving the platen away from the work sheets, and thereafter line spacing the work sheets and feeding the strips endwise.

44. A manifolding device comprising a travelling carriage, a non-rotatable platen supported thereon, means for supporting a plurality of work sheets over said platen, means for supporting a plurality of carbon strips interleaved with said work sheets, a carriage return lever, and means operated by the carriage return lever for imposing a frictional resistance upon said strips and moving the platen away from the work sheets, and thereafter line spacing the work sheets and feeding the strips endwise.

45. A manifolding device comprising a travelling carriage, a non-rotatable platen supported thereon, means for supporting a plurality of work sheets over said platen, means for supporting a plurality of carbon strips interleaved with said work sheets, a carriage return lever, and means operated by the carriage return lever for imposing a frictional resistance upon said strips and moving the platen away from the work sheets, and thereafter line spacing the work sheets and feeding the strips endwise, all these operations being performed by moving the lever in a direction to return the carriage.

46. A manifolding device comprising a spindle extending rearwardly from the main frame, and adapted to receive a plurality of rolls of carbon strips, separating plates having key hole slots to fit over said spindle and tension means engaging said strips as they are fed from the rolls.

47. A manifolding device comprising a platen over which continuous work sheets and a record work sheet are fed, means for supporting and feeding a plurality of transverse carbon strips interleaved with said work sheets, means for guiding the continuous work sheets to the platen, separate means for guiding the record work sheet to the platen, means for line spacing said sheets, and means for effecting relative separation between the sheets and the platen during the line spacing movement.

48. A manifolding device comprising a platen over which continuous work sheets and a record work sheet are fed, means for supporting and feeding a plurality of carbon strips interleaved with said work sheets, a chute for guiding the continuous work sheets to the platen, a separate chute for guiding the record work sheet to the platen, means for line spacing said sheets, and means for effecting relative separation between the sheets and the platen during the line spacing movement.

49. A manifolding device comprising a platen over which continuous work sheets and a record work sheet are fed, means for supporting and feeding a plurality of transverse carbon strips interleaved with said work sheets, means for guiding the continuous work

sheets to the platen, separate means for guiding the record work sheet to the platen, means for giving all of said sheets a simultaneous line space movement, and means for effecting relative separation between the sheets and the platen during the line spacing movement.

50. A manifolding device comprising a platen over which continuous work sheets and a record work sheet are fed, means for supporting and feeding a plurality of transverse carbon strips interleaved with said work sheets, a chute for guiding the continuous work sheet to the platen, a separate chute for guiding the record work sheet to the platen, means for giving all of said sheets a simultaneous line space movement, and means for effecting relative separation between the sheets and the platen during the line spacing movement.

51. In a manifolding device, a non-rotatable platen over which work sheets are fed, means for supporting a plurality of carbon strips interleaved with and transverse to said sheets, a line spacing mechanism for the work sheets, means for feeding said carbon strips, and means for separating the work sheets and platen and for operating both the line spacing mechanism and the carbon strip feeding mechanism while the work sheets and platen are separated.

52. In a manifolding device, a non-rotatable platen over which work sheets are fed, means for supporting a plurality of carbon strips interleaved with and transverse to said sheets, a line spacing mechanism for the work sheets, means for feeding said carbon strips, and means including a single manually operable lever for separating the work sheets and platen and for operating both the line spacing mechanism and the carbon strip feeding mechanism while the work sheets and platen are separated.

53. In a manifolding device, a non-rotatable platen over which work sheets are fed, means for supporting a plurality of carbon strips interleaved with and transverse to said sheets, a line spacing mechanism for the work sheets, means for feeding said carbon strips, and means for moving the platen away from the work sheets and for operating both the line spacing mechanism and the carbon strip feeding mechanism while the work sheets and platen are separated.

54. In a manifolding device, a non-rotatable platen over which work sheets are fed, means for supporting a plurality of carbon strips interleaved with and transverse to said sheets, a line spacing mechanism for the work sheets, means for feeding said carbon strips, and means including a single manually operable lever for moving the platen away from the work sheets and for operating both the line spacing mechanism and the carbon strip feeding mechanism while the work sheets and platen are separated.

55. In a manifolding device, a platen, means for supporting a plurality of work sheets in cooperative relation thereto, a plurality of paper carbon strips interleaved with the work sheets and extending transversely thereof, a tension means for the strips located at one side of the work sheets, a pair of intermeshing corrugated feed rolls between which the carbon strips are positioned and correspondingly corrugated by said rolls, said feed rolls being located at the other side of the work sheets, and means for intermittently rotating said rolls to feed said strips through said tension means including a driving pawl directly engaging the corrugations of one of said rolls.

56. In a manifolding device, a platen, means for supporting a plurality of work sheets in cooperative relation thereto, a plurality of paper carbon strips interleaved with the work sheets and extending transversely thereof, a tension means for the strips located at one side of the work sheets, a pair of intermeshing corrugated feed rolls between which the carbon strips are positioned and correspondingly corrugated by said rolls, said feed rolls being located at the other side of the work sheets, and means for intermittently rotating said rolls to feed said strips through said tension means including a holding pawl directly engaging the corrugations of one of said rolls.

57. In a manifolding device, a platen, means for supporting a plurality of work sheets in cooperative relation thereto, a plurality of paper carbon strips interleaved with the work sheets and extending transversely thereof, a tension means for the strips located at one side of the work sheets, a pair of intermeshing corrugated feed rolls between which the carbon strips are positioned and correspondingly corrugated by said rolls, said feed rolls being located at the other side of the work sheets, and means for intermittently rotating said rolls to feed said strips through said tension means including a driving pawl and a holding pawl directly engaging the corrugations of one of said rolls.

58. In a manifolding device having a carriage for supporting a plurality of work sheets and a plurality of carbon strips interleaved therewith over the printing line, a feeding means common to all of the carbon strips and located at one side of the machine, and means including a combined carriage return and strip feeding lever located at the other side of the machine for actuating said carbon strip feeding means.

59. A manifolding device comprising printing mechanism as one element, a frame including a platen and adapted for normally supporting a plurality of work sheets in tight compact engagement with said platen and comprising another element, means for supporting a plurality of carbon strips inter-

- leaved with and compacted with said work sheets, said elements being relatively movable for letter spacing, and a single manually operable device for effecting relative return movement between said elements, for relieving the normal compact engagement of the work sheets and carbon strips with the platen and line spacing of said work sheets, and feeding said strips. 5 70
- 10 60. A manifolding device comprising printing mechanism as one element, a movable frame including a platen and adapted for supporting a plurality of work sheets and comprising another element, said frame being 75 normally inclined to compact the work sheets against the platen, means for supporting a plurality of carbon strips interleaved with and compacted with said work sheets, said elements being relatively movable for letter 80 spacing, and a single manually operable device for moving the frame from its inclined position to relieve the compacted engagement of the carbon strips and work sheets with the platen and for line spacing said work sheets, 85 20 and for effecting a relative return movement of said elements. 25
61. A manifolding device comprising printing mechanism as one element, a movable frame including a platen and adapted for supporting a plurality of work sheets and comprising another element, said frame being normally inclined to compact the work sheets against the platen, means for supporting a plurality of carbon strips interleaved with and compacted with said work sheets, said elements being relatively movable for letter spacing, and a single manually operable device for moving the frame from its inclined position to relieve the compacted engagement of the carbon strips and work sheets with the platen, and for effecting a relative return movement of said elements. 30 90
- 35 62. A manifolding device comprising a traveling carriage, a normally inclined platen carrying frame pivoted on said carriage and adapted for supporting a plurality of work sheets in compact engagement with the platen, means for supporting a plurality of carbon strips interleaved with and compacted with said work sheets, a carriage return lever, and means operated by said carriage return lever for swinging the frame to relieve the compacted engagement of the carbon strips and work sheets with the platen, and thereafter line space said work sheets. 40 95
- 45 63. A manifolding device comprising a traveling carriage, a normally inclined platen carrying frame pivoted on said carriage and adapted for supporting a plurality of work sheets in compact engagement with the platen, means for supporting a plurality of carbon strips interleaved with and compacted with said work sheets, a carriage return lever, and means operated by said carriage return lever for swinging the frame to relieve the compacted engagement of the carbon strips and work sheets with the platen, and thereafter line space said work sheets. 50 100
- 55 64. A manifolding device comprising a traveling carriage, a platen on the carriage, a frame pivoted on said carriage and adapted for supporting a plurality of work sheets, said frame being normally inclined to hold the work sheets compacted against the platen, means for supporting a plurality of carbon strips interleaved with and compacted with said work sheets, a manually operable member on said carriage, and means operated by said member for swinging said frame from its inclined position to relieve the compacted relation of the work sheets with the platen. 60 105
65. A manifolding device comprising a traveling carriage, a platen on the carriage, a frame pivoted on said carriage and adapted for supporting a plurality of work sheets, said frame being normally inclined to hold the work sheets compacted against the platen, means for supporting a plurality of carbon strips interleaved with and compacted with said work sheets, a manually operable member on said carriage, and means operated by said member for placing a frictional resistance upon said strips and swinging the frame away from its normally inclined position to relieve the compacted relation of the work sheets with the platen. 65 110
- 70 66. A manifolding device comprising a traveling carriage, a normally inclined platen carrying frame pivoted on said carriage and adapted for supporting a plurality of work sheets in compact engagement with the platen, means for supporting a plurality of carbon strips interleaved with and compacted with said work sheets, a carriage return lever, and means operated by said carriage return lever for swinging the frame to relieve the compacted engagement of the carbon strips and work sheets with the platen. 75 115
- 75 67. In a manifolding device, a platen in front of which work sheets are disposed and with which said work sheets normally compactly engage, means for supporting a plurality of carbon strips interleaved with and transverse to said sheets and compacted therewith, a line spacing mechanism for the work sheets, means for feeding said carbon strips, and means for relieving the compact engagement of the work sheets and carbon strips with the platen and for operating both the line spacing mechanism and the carbon strip feeding mechanism while the compact engagement between the work sheets and platen is relieved. 80 120
- 80 68. In a manifolding device, a platen in front of which work sheets are disposed and with which said work sheets normally com- 85 125
- 85 90 95 100 105 110 115 120 125 130

pactly engage, means for supporting a plurality of carbon strips interleaved with and transverse to said sheets and compacted therewith, a line spacing mechanism for the work sheets, means for feeding said carbon strips, and means including a single manually operable lever for relieving the compact engagement of the work sheets and carbon strips with the platen and for operating both the line spacing mechanism and the carbon strip feeding mechanism while the work sheets and platen compact engagement is relieved.

69. In a manifolding device, a platen in front of which work sheets are disposed and with which said work sheets normally compactly engage, means for supporting a plurality of carbon strips interleaved with and transverse to said sheets and compacted therewith, a line spacing mechanism for the work sheets, means for feeding said carbon strips, and means for moving the platen to relieve the compact engagement of the carbon strips and work sheets with the platen and for operating both the line spacing mechanism and the carbon strip feeding mechanism while said compact relation is relieved.

70. In a manifolding device, a platen in front of which work sheets are disposed and with which said work sheets normally compactly engage, means for supporting a plurality of carbon strips interleaved with and transverse to said sheets and compacted therewith, a line spacing mechanism for the work sheets, means for feeding said carbon strips, and means including a single manually operable lever for moving the platen to relieve the compact engagement of the carbon strips and work sheets with the platen and for operating both the line spacing mechanism and the carbon strip feeding mechanism while said compact relation is relieved.

71. In a manifolding typewriting machine, a main frame, a carriage movable on the frame, a platen on the carriage, means for positioning a plurality of work sheets in cooperative relation with said platen, carbon strip spools supported directly upon said main frame and maintained against bodily movement with said carriage, and means on the carriage to guide the carbon strips delivered from said spools in interleaved relation with said work sheets and along the printing line of the platen.

72. In a manifolding typewriting machine, a main frame, a carriage movable on the frame, a platen on the carriage, means for positioning a plurality of work sheets in cooperative relation with said platen, a spindle projecting rearwardly from the frame in a direction at right angles to the direction of movement of the carriage, a plurality of carbon strip spools supported on the spindle, and means on the carriage to guide the car-

bon strips delivered from said spools in interleaved relation with said work sheets.

73. In a manifolding typewriting machine, a main frame, a carriage movable on the frame, a platen on the carriage, means for positioning a plurality of work sheets in cooperative relation with said platen, carbon strip spools supported directly upon said main frame and maintained against bodily movement with said carriage, carbon strip feeding means disposed at the right hand side of the machine, and means to guide the carbon strips delivered from the spools first in a direction parallel to the carriage travel and in letter space direction, thence in a line at right angles to the carriage travel at the left hand side of the machine, thence longitudinally in front of the platen and interleaved with the work sheets in a direction opposite the letter space direction, thence in a line at right angles to the carriage travel at the right hand side of the machine into cooperative relation with said feeding means.

74. In a manifolding typewriting machine, a main frame, a carriage movable on the frame, a platen on the carriage, means for positioning a plurality of work sheets in cooperative relation with said platen, a spindle projecting rearwardly from the frame in a direction at right angles to the direction of movement of the carriage, a plurality of carbon strip spools supported on the spindle, and means on the carriage to guide the carbon strips delivered from said spools in interleaved relation with said work sheets, said work sheet positioning means including guiding means extending rearwardly beyond the platen, and said spools being disposed beneath said rearwardly extending guiding means.

75. In a manifolding typewriting machine, a main frame, a carriage movable on the frame, a platen on the carriage, means for positioning a plurality of work sheets in cooperative relation with said platen, carbon strip spools independently and freely rotatably supported directly upon said main frame and maintained against bodily movement with said carriage, carbon strip feeding means disposed at the right hand side of the machine, means to guide the carbon strips delivered from the spools first in a direction parallel to the carriage travel and in letter space direction, thence in a line at right angles to the carriage travel at the left hand side of the machine, thence longitudinally in front of the platen and interleaved with the work sheets in a direction opposite the letter space direction, thence in a line at right angles to the carriage travel at the right hand side of the machine into cooperative relation with said feeding means, and means disposed at the left hand side of the machine and engaging said carbon strips to impose a tension thereon.

76. In a manifolding device, a platen past which work sheets are fed, a line spacing mechanism for the work sheets, means for supporting a plurality of carbon strips interleaved with said work sheets, and means for relatively moving the work sheets and platen through a fixed degree of movement for separating the work sheets and platen and for operating the line spacing mechanism and for feeding the carbon strips endwise subsequent to the completion of said relative movement and while the work sheets and platen are separated.

77. In a manifolding device, a platen past which work sheets are fed, a line spacing mechanism for the work sheets, means for supporting a plurality of carbon strips interleaved with said work sheets, and means including a single manually operable lever for relatively moving the work sheets and platen through a fixed degree of movement for separating the work sheets and platen and for operating the line spacing mechanism and for feeding the carbon strips endwise subsequent to the completion of said relative movement and while the work sheets and platen are separated.

78. In a manifolding device, a platen past which work sheets are fed, a line spacing mechanism for the work sheets, means for supporting a plurality of carbon strips interleaved with said work sheets, and means for moving the platen away from the work sheets and interleaved carbons a predetermined fixed distance and for operating the line spacing mechanism subsequent to the completion of said platen movement and while the work sheets and platen are separated.

79. In a manifolding device, a platen past which work sheets are fed, a line spacing mechanism for the work sheets, means for supporting a plurality of carbon strips interleaved with said work sheets, and means including a single manually operable lever for moving the platen away from the work sheets and interleaved carbons a predetermined fixed distance and for operating the line spacing mechanism subsequent to the completion of said platen movement and while the work sheets and platen are separated.

80. In a manifolding device, a platen past which work sheets are fed, a frame over which the work sheets travel after leaving the platen and fixed to the platen, line spacing mechanism for the work sheets mounted on the frame, means for supporting a plurality of carbon strips interleaved with said work sheets, and means for moving the frame and platen to separate the platen from the work sheets and interleaved carbon strips and for operating the line spacing mechanism while the work sheets and interleaved carbon strips and the platen are separated.

81. In a manifolding device, a platen past which work sheets are fed and which sheets

tightly and compactly engage said platen prior to and during printing intervals, means for supporting a plurality of carbon strips interleaved with and compacted with said work sheets, a line spacing mechanism for the work sheets, and means for relieving said tight and compact engagement between the work sheets and carbon strips and platen and for operating the line spacing mechanism while such engagement is relieved.

82. In a manifolding device, a platen past which work sheets are fed and which sheets tightly and compactly engage said platen prior to and during printing intervals, means for supporting a plurality of carbon strips interleaved with and compacted with said work sheets, and means including a single manually operable lever for relieving said tight and compact engagement between the work sheets and carbon strips and platen and for operating the line spacing mechanism while such engagement is relieved.

83. In a manifolding device, a platen past which work sheets are fed, a frame over which the work sheets travel after leaving the platen and fixed to the platen, means for supporting a plurality of carbon strips interleaved with said work sheets, line spacing mechanism for the work sheets mounted on the frame, and means for moving the frame and platen between printing and non-printing positions in which the platen tightly engages and compacts the work sheets and carbon strips and in which said platen is relieved from such engagement respectively, and for operating the line spacing mechanism while the platen is relieved from such engagement.

84. In a manifolding device, the combination with a platen having a transversely curved printing surface, of means for guiding work sheets from below the platen to above the platen and in a substantially flat vertical condition in front of the platen, means for supporting a plurality of carbon strips interleaved with said work sheets and extending lengthwise of the platen and in front thereof, and means for effecting relative movement between the work sheets and carbon strips and the platen whereby the work sheets and carbon strips will be curved to conform to and tightly compact the printing surface of the platen.

85. In a manifolding device, the combination with a platen provided with a transversely curved printing surface, of means respectively disposed above and below the platen for positioning the work sheets in a substantially flat vertical condition in front of the platen, means for supporting a plurality of carbon strips interleaved with said work sheets and extending lengthwise of the platen and in front thereof, and means for bodily moving the platen to engage the work sheets between the respective positioning means and curve said sheets and strips to

conform to and tightly compact the printing surface of the platen.

86. In a manifolding device the combination with a platen provided with a transversely curved printing surface, of means respectively disposed above and below the platen for positioning the work sheets in a substantially flat vertical condition in front of the platen, means for supporting a plurality of carbon strips interleaved with said work sheets and extending lengthwise of the platen and in front thereof, means for bodily moving the platen to engage the work sheets between the respective positioning means and curve said sheets and strips to conform to and tightly compact the printing surface of the platen, and means for effecting a line spacing movement to the work sheets while the latter are in substantially flat condition.

87. In a manifolding device, the combination with a typewriting machine having type arms and a platen arranged in cooperative relation, of a guide disposed above the platen, a holder disposed below the platen and movable to feed vertically disposed work sheets past the guide and platen and between the platen and the type arms, means for supporting a plurality of carbon strips interleaved with the said work sheets and extending lengthwise of the platen and in front thereof, and means for effecting a relative bodily movement between the platen and the guide for placing the work sheets and the carbon strips in tight compact relation with the printing line of the platen preparatory to certain printing operations by the type arms and for relieving the said tight compact relation between the work sheets, carbon strips and platen prior to the work sheets' feeding operation by the holder.

88. In a manifolding device, the combination with a typewriting machine having type arms and a platen arranged in cooperative relation, of a guide disposed above the platen, a holder disposed below the platen and movable to feed vertically disposed work sheets past the guide and platen and between the platen and the type arms, means for supporting a plurality of carbon strips interleaved with the said work sheets and extending lengthwise of the platen and in front thereof, and means including a single manually operable lever for effecting a relative bodily movement between the platen and the guide for placing the work sheets and the carbon strips in tight compact relation with the printing line of the platen preparatory to certain printing operations by the type arms and for relieving the said tight compact relation between the work sheets, carbon strips and platen prior to the work sheets' feeding operation by the holder.

89. In a manifolding device, the combination with a typewriting machine having type arms and a platen arranged in cooperative

relation, of a guide disposed at one side of the platen, a frame over which the work sheets travel after leaving the platen, said platen being fixed to the frame and the frame being located on the side of the platen opposite the guide, line spacing mechanism for the work sheets mounted on the frame for feeding the work sheets past the guide and platen and between the platen and the type arms, means for supporting a plurality of carbon strips interleaved with the said work sheets, and means for bodily moving the platen between printing and non-printing positions in which the platen tightly engages and compacts the work sheets and carbon strips and in which said platen is relieved from such engagement respectively, and for operating the line spacing mechanism while the platen is relieved from such engagement.

90. In a manifolding device the combination with a typewriting machine having type arms and a platen arranged in cooperative relation, of a guide disposed at one side of the platen, a frame over which the work sheets travel after leaving the platen, said platen being fixed to the frame and the frame being located on the side of the platen opposite the guide, line spacing mechanism for the work sheets mounted on the frame for feeding the work sheets past the guide and platen and between the platen and the type arms, means for supporting a plurality of carbon strips interleaved with the said work sheets, and means including a single manually operable lever for bodily moving the platen between printing and non-printing positions in which the platen tightly engages and compacts the work sheets and carbon strips and in which said platen is relieved from such engagement respectively, and for operating the line spacing mechanism while the platen is relieved from such engagement.

91. In a manifolding device, the combination with a typewriting machine having type arms and a platen arranged in cooperative relation, of a guide disposed above the platen and fixed against bodily movement relative thereto, a holder disposed below the platen and movable to feed vertically disposed work sheets past the guide and platen and between the platen and the type arms, means for supporting a plurality of carbon strips interleaved with said work sheets extending lengthwise of the platen and in front thereof, and means for effecting bodily movements of the holder and platen in opposite directions simultaneously for placing the work sheets and carbon strips in tight compact with the printing line of the platen preparatory to certain printing operations of the type arms and for relieving said tight, compact relation between the work sheets, carbon strips and platen prior to the work sheets' feeding operation by the holder.

92. In a manifolding device, a platen past

which work sheets are fed, a clamp for the leading ends of the work sheets, a pivoted frame over which said clamp moves for line spacing said work sheets, means for supporting a plurality of carbon strips interleaved with said work sheets, said frame being normally inclined rearwardly to maintain the work sheets and carbon strips in tight compact relation with the platen, and means for 5 swinging the frame forwardly from said rearwardly inclined position to a substantially vertical position whereby said work sheets and carbon strips will be relieved of said tight compact relation with the platen and 10 for effecting line spacing movement of the clamp while the frame is in said substantially vertical position.

93. In a manifolding device, a platen past 20 which work sheets are fed, a clamp for the leading ends of the work sheets, a pivoted frame over which said clamp moves for line spacing said work sheets, means for supporting a plurality of carbon strips interleaved with said work sheets, said frame being normally inclined rearwardly to maintain the work sheets and carbon strips in tight compact relation with the platen, means for 25 swinging the frame forwardly from said rearwardly inclined position to a substantially vertical position whereby said work sheets and carbon strips will be relieved of said tight compact relation with the platen and for effecting line spacing movement of the clamp while the frame is in said substantially vertical position.

94. In a manifolding device, a platen past which work sheets are fed, a clamp for the leading end of the work sheets, a pivoted frame over which said clamp moves for line spacing said work sheets, means for supporting a plurality of carbon strips interleaved with said work sheets, said frame being normally inclined rearwardly to maintain the work sheets and carbon strips in tight compact relation with the platen, means for swinging the frame forwardly from said rearwardly inclined position to a substantially vertical position whereby said work sheets and carbon strips will be relieved of said tight compact relation with the platen and for effecting line spacing movement of the clamp while the frame is in said substantially vertical position, and means for releasing said clamp from said line space effecting means.

95. In a manifolding device, a platen past which work sheets are fed, a clamp for the leading ends of the work sheets, a pivoted frame over which said clamp moves for line spacing said work sheets, means for supporting a plurality of carbon strips interleaved with said work sheets, said frame being normally inclined rearwardly to maintain the work sheets and carbon strips in tight compact relation with the platen, means for swinging the frame forwardly from said rearwardly inclined position to a substantially vertical position whereby said work sheets and carbon strips will be relieved of said tight compact relation with the platen and for effecting line spacing movement of the clamp while the frame is in said substantially vertical position, and means for releasing said clamp from said work sheets.

96. In a manifolding device, a platen past which work sheets are fed, a clamp for the leading ends of the work sheets, a pivoted frame over which said clamp moves for line spacing said work sheets, means for supporting a plurality of carbon strips interleaved with said work sheets, said frame being normally inclined rearwardly to maintain the work sheets and carbon strips in tight compact relation with the platen, means for swinging the frame forwardly from said rearwardly inclined position to a substantially vertical position whereby said work sheets and carbon strips will be relieved of said tight compact relation with the platen and for effecting line spacing movement of the clamp while the frame is in said substantially vertical position, and means for releasing said clamp from said line space effecting means and from said sheets.

pact relation with the platen, means for swinging the frame forwardly from said rearwardly inclined position to a substantially vertical position whereby said work sheets and carbon strips will be relieved of said tight compact relation with the platen and for effecting line spacing movement of the clamp while the frame is in said substantially vertical position, and means for releasing said clamp from said line space effecting means and from said sheets.

In testimony whereof, I have hereunto subscribed my name.

GUSTAVE O. DEGENER.
